UNITED STATES PATENT OFFICE.

HAROLD L. BLANCHARD, OF NORTHBIDGE, MASSACHUSETTS, ASSIGNOR TO CROMPTON & KNOWLES LOOM WORKS, OF WORCESTER, MASSACHUSETTS, A CORPORATION OF MASSACHUSETTS.

DEVICE TO PREVENT ROTATION OF BOBBINS.

Application filed April 2, 1924. Serial No. 703,605.

To all whom it may concern:

Be it known that I, HAROLD L. BLANCHARD, a citizen of the United States, residing at Northbridge, in the county of Worcester and 5 State of Massachusetts, have invented a new and useful Device to Prevent Rotation of Bobbins, of which the following is a specification.

This invention relates to weft replenishing mechanism for looms and more particularly to means for preventing the rotation of bobbins on their own axes as they await transfer.

In the usual form of multi-color weft replenishing mechanism the bobbins are arranged loosely in vertical parallel compartments and are fed one by one to transfer position. It has been found that where the 10 yarn is fine the bobbins are required to remain in the replenishing mechanism a sufficient length of time so that they roll on their axes and cause entanglement of the weft ends which extend to the thread holder.

It is the principal object of my invention 15 to avoid this undesirable rotation of the bobbins by exerting lateral pressure on them by means of a pivoted wall which forms part of the compartment and is under control of the replenishing mechanism so as to release 20 the bobbins to permit them to fall at the time of indication of weft exhaustion.

Another object of my invention is to provide adjacent bobbin compartments with pivoted walls held in bobbin restraining position by a plurality of spaced yielding devices which permit either wall to move under control of the replenishing mechanism independently of the other wall.

With these and other objects in view 25 which will appear as the description proceeds, my invention resides in the combination and arrangement of parts hereinafter described and set forth in the claims.

In the accompanying drawings wherein I 30 have shown one form of my invention,

Fig. 1 is a side elevation of a portion of the replenishing mechanism having my invention applied thereto,

Fig. 2 is a vertical section taken on line 35 2-2 of Fig. 1,

Fig. 3 is an enlarged detail section of the upper part of the structure shown in Fig. 2,

Fig. 4 is a horizontal section taken on line 40 4-4 of Fig. 1, and

Fig. 5 is a view similar to Fig. 4 but having one of the walls moved out of bobbin restraining position.

Referring to the drawings it will be seen that I have provided a replenishing mechanism having a frame 10 on which is mounted and guided for vertical motion the slides 11 and 12. These slides are provided with upper lugs 13 and 14, respectively, and lower lugs 15 and 16, respectively, and have the lower portions thereof so formed as to 55 actuate the bobbin controlling cradles (not shown). A longitudinally and angularly movable rod 17 is guided in bearings 18 projecting from the frame 10 and has secured thereto a finger 19 to cooperate with the lugs 13, 14, 15 and 16. The finger 19 has a downward motion every second pick of the loom and has an upward motion at indication of substantial weft exhaustion to raise one or the other of the slides 11 or 12, according to the shuttle which is active. The frame 10 has extending therefrom flanges 60 20 and 21 which form the outer boundaries 65 of the two bobbin compartments shown.

The matter thus far described is part of 70 the usual four color weft replenishing mechanism and for a further description of the same and its operation reference may be had to Patent No. 1,030,748.

My invention relates to the walls of the 75 bobbin guideways or compartments and contemplates the use of a fixed and a movable wall for each compartment, the movable wall being pivoted and normally moved against the bobbins to restrain the latter 80 against undue movement and moved from bobbin restraining position by the weft replenishing mechanism at the time the bobbins are called upon to descend in the guideway.

Referring more particularly to Figs. 2 to 85 4 it will be seen that I have provided the frame 10 with a lower lug 30 and an upper bearing stand 31 which is provided with slots 32 to receive bolts 33, the slots permitting a slight vertical adjustment of the bearing block 31. Rods 34 and 35 are provided, one for each bobbin compartment and have their upper ends threaded to be received by the threaded bores 36 and 37 of the member 31. The lower ends of the rods 90 extend loosely through and are held in position by the lug 30.

Associated with the rods 34 and 35 are walls 38 and 39, respectively, each of which is provided with upper and lower bearings 40 and 41, respectively, through which the rods extend. The bearings 41 rest on the lug 30 and thus support the walls, each of which moves pivotally about its corresponding rod as a center.

Extending from the walls 38 and 39 are ears 42 and 43, respectively, having formed thereon cams 44 and 45, respectively, positioned for the reception of pins 46 and 47 which are carried with the slides 11 and 12, respectively. By referring to Fig. 4 it will be seen that the movable walls have formed on the adjacent faces thereof bosses 48 between which extend compression springs 49, 50 and 51 which are disposed at different points along the walls so that the latter are acted upon at a plurality of points to move against the bobbins. To provide for variations in the diameters of the bobbins I have provided each movable wall with a covering of resilient material such as rubber or leather, indicated at 52.

In the normal operation of the replenishing mechanism the slides 11 and 12 are down as indicated in Fig. 3 and the pins 46 and 47 are located at the lower ends of cams 44 and 45 respectively, thus permitting the springs 49, 50 and 51 to push the movable walls against the bobbins. At indication of weft exhaustion the slide corresponding to the indicating shuttle will be raised by finger 19, slide 11 being indicated by dotted lines as in raised position in Fig. 2. As this slide is raised, pin 46 engages cam 44 to move wall 38 away from bobbin restraining position as shown in Fig. 5, and the bobbins will therefore be free to fall as required by the operation of the replenishing mechanism. When the indicating shuttle returns to the weft replenishing side of the loom, slide 11 will be lowered by finger 19, and pin 46 will move away from cam 44 to enable the springs 49, 50 and 51 to again move wall 38 against the bobbins to restrain their rotation. Wall 39 is similarly controlled by slide 12.

From the foregoing it will be seen that I have provided a very simple means for restraining the rotation of bobbins by providing each compartment of the weft replenishing mechanism with a movable wall under control of the replenishing mechanism and having a surface to engage the bobbins and force them against the fixed wall of the compartment. It will further be seen that I have provided a pair of bobbin compartments with adjacent pivoted walls which have common resilient means for holding the walls against the bobbins.

Having thus described my invention it will be apparent that changes and modifications may be made therein by those skilled

in the art without departing from the spirit and scope of the invention and I do not wish to be limited to the details herein disclosed, but what I claim is:

1. In a weft replenishing mechanism for looms, a guideway to hold reserve bobbins as they await movement toward transfer position, a wall for said guideway mounted for pivotal movement about an axis substantially parallel to the direction in which the bobbins move in said guideway and extending adjacent the reserve bobbins, and means to move said wall pivotally to engage the bobbins in the guideway.

2. In a weft replenishing mechanism for looms, a compartment to hold reserve bobbins as they await movement toward transfer position, means defining one side of the compartment and mounted for pivotal motion about an axis substantially parallel to the direction in which the bobbins move in said compartment and extending adjacent the reserve bobbins, and means under control of the weft replenishing mechanism to move said first named means into engagement with the bobbins.

3. In a weft replenishing mechanism for looms, a compartment for bobbins, means defining one side of the compartment and pivotally mounted to move about an axis substantially perpendicular to the axes of the bobbins, and means to move said first named means against the bobbins.

4. In a weft replenishing mechanism for looms, a compartment to hold reserve bobbins as they await movement toward transfer position, a wall for the compartment extending upwardly from the discharge end of the compartment and extending adjacent the reserve bobbins and pivoted to move in a plane substantially parallel to the axes of the bobbins, and means to control the wall from the replenishing mechanism.

5. In a weft replenishing mechanism for looms, a bobbin compartment, and means under control of the replenishing mechanism to vary the width of the compartment uniformly throughout the length of said means to cause a variation in the width of the space occupied by the bobbins.

6. In a weft replenishing mechanism for looms, a bobbin compartment, and a wall for said compartment controlled by the replenishing mechanism and movable about an axis having a vertical component.

7. In a replenishing mechanism for looms, a pair of bobbin compartments, a pivoted wall for each compartment, the pivoted walls being independently movable, and means common to the walls tending to move the same toward the bobbins.

8. In a weft replenishing mechanism for looms, a pair of bobbin compartments, a pivoted wall for each compartment, and resilient means common to the walls to

permit independent movement of the walls with respect to each other and normally moving said walls toward the bobbins.

9. In a replenishing mechanism for looms, 5 a bobbin compartment, a vertically movable slide under control of the replenishing mechanism, a wall pivotally mounted about an axis transverse of the bobbins for said compartment normally restraining rotation 10 of the bobbins in the compartment, and operating connections between the vertical slide and the wall to move the latter away from the bobbins as the slide is raised.

10. In a weft replenishing mechanism for looms, a bobbin compartment, a wall pivotally mounted about an axis transverse of the bobbins for the compartment and held normally against the bobbins in the compartment, a vertically movable slide, a longitudinally and angularly movable finger, and 15 operating connections between the slide and the wall to move the wall away from the bobbins when the finger raises the slide.

In testimony whereof I have hereunto affixed my signature.

HAROLD L. BLANCHARD.
